VACUUM CLEANER BAG

Harry Kessler, Brooklyn, N. Y.

Application November 29, 1938, Serial No. 242,873

5 Claims. (Cl. 183—51)

This invention relates to improvements in vacuum cleaner bags.

Vacuum cleaner bags of the kind most commonly in use require the disconnection of the bag from the vacuum cleaner head and handle to facilitate the dumping of dust and dirt which is collected therein during use of the vacuum cleaner. Such practice is laborious and requires the shaking of the bag to thoroughly empty all the dust and dirt therefrom which stirs up the dust and makes the emptying of the bag a dirty and unpleasant operation. It is therefore one of the main features of this invention to provide a vacuum cleaner bag which may be emptied without disconnecting the same from the vacuum cleaner; and which may be easily and expeditiously emptied of accumulated dust and dirt in a clean manner.

Vacuum cleaner bags are in reality dust filter bags, that is, air may escape from the bag but any particles of dust and dirt blown into the bag becomes trapped therein. In my invention I provide a closure flap in the side wall of the bag, which flap when opened, uncovers an opening through which the accumulated dust and dirt may be emptied from the bag. It is therefore essential that some positive sealing means be provided between the closure flap and body of the bag when the flap is in closed position. Therefore, another important feature of the invention is to provide a positive dust-proof seal for the closure flap when the same is in closed position.

A further feature of the invention resides in a vacuum cleaner bag having a closure flap at the rear side and adjacent the bottom thereof, and a novel means associated with the closure flap for loosening any matted dust and dirt which may accumulate therein, as the closure flap is swung to an open position, thus making it unnecessary for an operator to reach into the bag to loosen the collected matter preparatory to its discharge through the discharge opening.

Another feature of the invention is the provision of a vacuum cleaner bag which receives an adapter by which it is possible to connect the bag to the many different makes of vacuum cleaners now upon the market.

A still further feature of the invention is the provision of a vacuum cleaner bag having a dust and dirt discharge opening in the rear thereof which is normally closed by a closure flap secured by a slide fastener device, the tapes of the stringers of the slide fastener device overlapping inwardly of the interlocking elements of the device

5 to seal the joint between the interlocking elements against the escape of dust and dirt therebetween, and to prevent particles of dust and dirt from interfering with the free operation of the slide fastener device.

A still further feature of the invention is to provide a novel means of attaching the top of the bag to the handle of a vacuum cleaner to support the same in a loose suspended position for use, and which means enables the lowering of the bag to a position adjacent the floor level for emptying without disconnecting the bag from the handle.

While I have set forth several novel features 15 of my improved vacuum cleaner bag, other features thereof will become apparent as the following specification is read in conjunction with the accompanying drawings, in which,

Figure 1 is a side elevation of a conventional 20 vacuum cleaner equipped with my improved dust collector bag and showing in dotted lines the approximate shape of the bag when inflated.

Figure 2 is a rear elevational view.

Figure 3 is a view similar to Figure 1 but showing 25 the bag in dust dumping position.

Figure 4 is a perspective view of the bag per 30 se showing the closure flap in open position.

Figure 5 is an enlarged fragmentary vertical 35 sectional view taken substantially on the line 5—5 of Figure 2.

Figure 6 is an enlarged detail vertical sectional view on the line 6—6 of Figure 2 with the bag inflated.

Figure 7 is an enlarged detail vertical sectional 40 view on the line 7—7 of Figure 2 with the bag inflated.

Figure 8 is an enlarged horizontal sectional 45 view on the line 8—8 of Figure 2.

Figure 9 is a detail vertical sectional view of a modified form of the invention.

Figure 10 is a detail horizontal sectional view 50 on the line 10—10 of Figure 9.

Figure 11 is an enlarged detail vertical sectional view of the slide fastener seal shown in 55 Figure 9.

Figure 12 is a fragmentary side elevational view of the modified form of bag shown in Figures 9 to 11 inclusive, and illustrating the bag in dirt dumping position.

Figure 13 is a detail vertical longitudinal sectional view through the neck of the bag and coupling sleeve.

Figure 14 is a detail vertical sectional view through the neck of the bag and adapter sleeve.

Referring to the drawings by reference char-

acters, the numeral 10 designates my improved vacuum cleaner bag in its entirety, and which includes an elongated bag body 11 closed at its top end by a seam 12 and having a restricted tubular neck portion 13 at its lower end. The bag body 11 is constructed of the usual filter cloth material, that is, the fabric permits air to pass outwardly from the inside of the bag without the escape of dust or dirt which is intended to be collected within the body. The bag body 11 includes a front piece of material 14 and a rear piece of material 15, the same being stitched together along the side edges as at 16. The rear wall 15 includes an upper section 17 having a closure flap 18 formed integral therewith, and a substantially U-shaped lower section 19, which is stitched to the upper section 17 at 20. The lower U-shaped section 19 defines a discharge opening 21 in the rear wall of the bag and the edges of the opening 21 are cross stitched or bound with tape as designated at 22. The closure flap 18 is of a shape corresponding to the opening 21 but is of a size to overlap the edges of the opening when the closure flap is in closed position. Stitched adjacent the free edges of the closure flap 18 is the stringer 23 of a slide fastener device, the said stringer being substantially parallel to the edges of the flap 18. Stitched to the outer side of the lower portion 19 of the rear wall of the bag body is the complementary slide fastener stringer member 24, the same being set inwardly of the edge of the opening 21 and substantially parallel thereto, the portion of the section 19 disposed inwardly of the stringer member 24 constituting a sealing flap 25. Each of the stringers 23 and 24 includes a flexible attaching tape 26 on which the interlocking fastener elements are carried intermediate the longitudinal side edges to provide a sealing flap 27 which laps the interlocking fastener elements of the stringer member. The flaps 27 of the stringer members 23 and 24 overlap inwardly of the interlocking elements when the latter are in interlocking engagement, whereas to provide a seal at the inner side of the stringers to prevent dust and dirt from passing through the joints and from interfering with the free operation of the slide fastener device. The slide fastener device also includes the usual manual operated slider 28 which effects interlocking of the stringers and the release thereof during the sealing and opening of the flap 18.

The closure flap 18 is provided with a transversely disposed pleat or fold 29, which fold lies flat when the bag body is in a flattened position and which provides a dust and dirt accumulating pocket 30 when the bag body is inflated by the air blown thereinto from the suction head of the vacuum cleaner.

Fitting into the reduced tubular neck 13 of the bag body is the inner end of a coupling sleeve 31, the said sleeve having an external circumferential groove 32 therein with which a wire ring 33 co-acts for clamping the coupling sleeve 31 in the neck 13. The coupling sleeve 31 is secured to the neck when the bag is being constructed inside out so that all seams are on the inside of the bag and the clamping ring 33 is concealed. A portion of the restricted neck 13 which is designated 34 in Figure 13 extends inwardly of the neck beyond the coupling sleeve 31 to provide a flappy baffle which will permit air and dirt to enter the bag through the neck and which tends to trap any dust or dirt from passing out through the neck after the operation of the suction head of

the vacuum head has been shut off. The outer end of the coupling sleeve 31 is provided with any conventional form of attaching means for the purpose of fitting a complementary coupling member on the discharge spout of the vacuum cleaner head. In Figure 13, a conventional bayonet slot 35 is shown and which might be used in vacuum cleaner machines having pins on the complementary coupling elements.

The seam 12 at the top of the bag is formed when the bag is inside out during the making of the same and secured in the hem formed by this seam is a transversely disposed reinforcing bar 36 to which one end of a suspension strap 37 is connected. The end of the strap 37 is looped about the bar 36 and held by the hem formed by the two lines of stitching 38. Carried by the free end of the strap 37 is a female snap fastener element 39 which is adapted to be engaged with the male snap fastener element 40' on the rear wall 15 of the bag body or if desired the element 40' may be attached to the strap adjacent the bag body. The strap 37 passes through a restricted slot 40 in a buckle 41', the said buckle also being formed with an attaching eye 42. The slot 40 is of such size as to permit of the free sliding movement of the strap 37, but which prevents the fastener element 39 from passing through the slot, thus the buckle 41' is captively connected to the strap 37.

Stitched to the inner side of the front wall 14 of the bag body just above the neck portion thereof is one end of a flexible ejector strap 41, the other end of the strap being stitched to the extreme end of the closure flap 18. The strap 41 is of a length to provide slack therein when the closure flap 18 is closed, whereupon the strap 41 folds upon itself as indicated in Figure 5, but upon opening of the closure flap 18 to expose the opening 21, the strap 41 becomes taut and acts as an ejector for loosening and ejecting matted or bunched dirt and dust from within the bag and in the direction of the discharge opening 21.

In Figures 1 to 3, inclusive, I have illustrated my improved vacuum cleaner bag in position upon a conventional vacuum cleaner A of the "Hoover" type which includes broadly a suction head B and a handle C pivotally connected to the head B. The head B is provided with a discharge spout D at the rear thereof which has a coupling member E adapted to receive the coupling sleeve 31. As previously mentioned, a bayonet slot coupling has been shown, but the showing is merely illustrative and may vary according to the complementary coupling members of the different makes of vacuum cleaners. The coupling sleeve 31 connects the reduced neck portion of the bag body 11 to the suction head B and fixedly secured on the handle C at the rear thereof and just below the hand grip portion, there is a hook F which receives the eye 42 of the buckle 41'. With the snap fastener element 39 engaged with the element 40', it will be noted in Figures 1 and 2 that the strap 37 forms a suspending loop for the upper end of the bag and normally the bag assumes the position shown in full lines in Figure 1 and when the bag is inflated under the air pressure exhausted thereinto by the vacuum cleaner head B, the bag bellies out to substantially the position shown in dotted lines in Fig. 1. During use of the vacuum cleaner, dust and dirt which enters the bag 10 from the suction head B will settle adjacent the bottom of the bag or in the vicinity of the closure flap 18, the said dirt and dust having a tendency to bunch up or mat due to the

nap, threads, and other particles of dust and dirt deposited into the bag from the vacuum cleaner head B. Assume that it is desired to empty the bag 10 of collected dust and dirt. The operator disconnects the snap fastener element 39 from the snap fastener element 40, thus unloosening the looped strap 37 and which permits the top closed end of the bag to drop, the extent of the dropping movement of the bag being approximately the length of the strap 37 for the strap 37 pays out until the snap fastener element 39 engages the buckle 41. The operator now places a newspaper G upon the floor as illustrated in Figure 3 and positions the paper so that it will lie directly beneath the discharge opening 21 of the bag after opening of the flap 18. The operator next grasps the slider 28 and moves it from one end of the stringers to the opposite ends, thus unfastening the flap which enables the operator to grasp the end of the flap and fold the same outward in the direction of the top end of the bag. As the flap 18 is swung open, the ejector strap 41 is drawn taut, thus tending to loosen any bunched or matted dirt and dust which might be present within the bag. When the closure flap 18 is swung to the substantially horizontal open position as illustrated in Figure 3 of the drawings, it provides a shield to arrest the rising of dust and dirt during the bag emptying operation. After the bag has been emptied, the slider 28 is actuated to bring the interlocking fastener elements of the fastener device into locked position, and the free end of the strap 37 is grasped and the strap pulled through the eye 40 and the snap fastener element 39 is engaged with the snap fastener element 40, thus bringing the top of the bag to its normal position.

When the closure flap 18 is closed by the slide fastener device, the joint between the interlocking elements of the slide fastener device are sealed by a double sealing means, namely the sealing flap 35 which is blown outward against the closure flap 18 when the bag is inflated, and secondly, the overlapping sealing tapes 27 which are associated with the respective stringer members 23 and 24.

In Figures 9 to 12 inclusive, I have illustrated certain modified features of construction, and parts corresponding to those hereinbefore described are designated by like reference characters.

In the modification shown in Figures 9 and 11 the sealing flap 25 is dispensed with and the stringer member 24 of the slide fastener device is secured to the front wall of the bag body around the edges of the opening 21. Instead of relying upon the flap 25, I substitute therefor, a sealing strip which includes a rubberized flexible strip of tape folded upon itself to provide an attaching portion 42' and encloses a rubber yieldable bead 43. The attaching portion 42' of the beaded sealing strip is secured by stitching 44 which also aids in securing the stringer 24 to the rear wall of the bag. In this construction, the yieldable sealing bead 43 tightly engages the overlapped sealing tapes 27 of the slide fastener device and coats therewith to provide a double seal to prevent dust and dirt from passing out through the joints between the interlocking elements of the stringers 23 and 24.

Another modified feature shown in Figures 9, 10 and 12 resides in a dust loosening and ejector member which may be substituted for the flexible strap 41 hereinbefore described. In lieu of the strap 41, I employ a pair of link members 45—45

which have their inner ends hingedly connected together as at 46, whereas the outer end of one of the members 45 is flexibly attached to the inside of the closure flap 18 by leather straps or tabs 47. The outer end of the other member 45 is connected to the inner side of the front wall 14 of the bag body by flexible straps or tabs 48. When the closure flap 18 is in closed position as illustrated in Figure 9, the link members 45 are folded into an inverted V, and upon opening of the closure flap 18 as illustrated in Figure 12 of the drawings, the link members 45 separate and the hinge joint breaks outwardly to forcibly eject any accumulated bunched or matted dirt contained within the bag.

In Figure 14 of the drawings, I have illustrated a construction which will enable the neck of the bag to be equipped with a standard fitting capable of interchangeably receiving an adapter having attaching means complementary to the coupling of any well-known make of vacuum cleaner. In Figure 14 I provide a coupling collar 31' which is connected to the neck of the bag in the same manner as the coupling collar 31 hereinbefore described. The outwardly extending portion of the coupling collar is formed with an annular shoulder 49 which has its outer face undercut as at 50 for receiving the beveled end 51 of an adapter 52. The beveled end of the adapter 52 is also provided with a bead 53, which bead is engaged by a pair of diametrically opposed snap spring members 54 which are carried by the collar 31'. Whereas the adapter member 52 is shown as having its outer end provided with a bayonet slot 55, other forms of connecting elements may be provided depending upon the type of connection with which the various makes of vacuum cleaners are provided.

From the foregoing description, it will be seen that I have provided a vacuum cleaner bag which is adaptable for use on the different makes of vacuum cleaners and in which the bag may be emptied of its accumulated dust and dirt without necessitating the disconnection of the bag from the vacuum cleaner head and handle of the vacuum cleaner machine. The dust and dirt emptying operation may be cleanly accomplished without stirring up the dust and dirt and with a minimum amount of labor to an operator.

While I have illustrated in the drawings, one particular shape of my vacuum cleaner bag, it will be understood that the shapes may vary according to the particular type of vacuum cleaners to which the bags are adapted for use.

Having described what I consider to be the most practical embodiments of my invention, I wish it to be understood that such changes and alterations as come within the scope of the appended claims may be resorted to if desired.

Having thus described the invention, what I claim as new and desire to secure by Letters Patent of the United States, is:

1. A vacuum cleaner bag comprising a body closed at its upper end and having an open neck at its lower end, said body having a discharge opening in one of the side walls and disposed adjacent the lower end thereof, a closure flap connected to said body for closing said opening, releasable fastening for securing said closure flap in closed position over said opening, and dirt ejector means connected to said closure flap and opposed wall of said body and normally folded therein for unfolding to eject accumulated dirt from said body toward said discharge opening.

when said fastening means is released and said closure flap is swung to open position.

2. A vacuum cleaner bag comprising a body closed at its upper end and having an open neck at its lower end, a substantially U-shaped slit provided in the rear side of said body adjacent the lower end thereof, said slit providing a discharge opening and a closure flap for overlying said opening, a single slide closure device for securing said flap in closed position over said opening, and a flexible strap having one of its ends secured to the inner front side of said body and its other end attached to the free end of said closure flap, said strap having sufficient slack therein as to normally fold into said body when said closure flap is in closed position and to enable opening of said flap during which time the strap is moved to a taut position to urge any accumulated dirt in the bag toward the discharge opening.

3. A vacuum cleaner bag comprising a body closed at its upper end and having an open neck at its lower end, a substantially U-shaped slit provided in the rear side of said body adjacent the lower end thereof, said slot providing a discharge opening and a closure flap for overlying said opening, a single slide closure device for securing said flap in closed position over said opening, a pair of rigid links pivoted together at their inner ends, the outer ends of said links being respectively hingedly connected to the inner front side of said body and to the free end of said closure flap, said pivoted links being folded within said body when said closure flap is in closed position and adapted to unfold and forcibly urge any accumulated dirt in said body toward the discharge opening when said closure flap is in open position.

4. In combination with a vacuum cleaner having a handle, a filter bag closed at its top, an inlet opening at the lower end of said bag, a discharge opening adjacent said inlet opening, means for connecting the top end of said bag to said handle, said means comprising an eye member carried by said handle, a strap freely passing through said eye member and having one of its ends fastened to the top of said bag, and releasable fastening elements on the other end of said strap and said bag to effect a looping of said strap, the fastening element on said strap being larger than the eye opening in said eye member to prevent said strap from pulling free of said eye member when said fastening elements are released whereby a limited lowering of the bag relative to said handle is effected to facilitate emptying said bag through said discharge opening.

5. In combination with a vacuum cleaner having a handle, a filter bag closed at its top, an inlet opening at the lower end of said bag, a discharge opening adjacent said inlet opening, means for connecting the top end of said bag to said handle, said means comprising an eye member carried by said handle, a strap freely passing through said eye member and having one of its ends fastened to the top of said bag, releasable fastening means connecting the free end of said strap to said bag to effect looping of said strap, and a stop element adjacent the free end of said strap which is larger than the eye opening in said eye member to prevent the strap from pulling free of said eye member when the fastening means is released whereby a limited lowering of the bag relative to said handle is effected to facilitate emptying of said bag through said discharge opening.

HARRY KESSLER.
